GEORGE F. ROSE, OF NEW YORK, N. Y.

RIBBON MECHANISM FOR TYPE-WRITERS.

1,189,627.

Specification of Letters Patent.

Patented July 4, 1916.

Application filed November 7, 1912. Serial No. 729,931.

To all whom it may concern:

Be it known that I, GEORGE F. ROSE, a citizen of the United States, residing at the city of New York, borough of Manhattan, county and State of New York, have invented a certain new and useful Ribbon Mechanism for Type-Writers, of which the following is a specification.

This invention is a ribbon mechanism for typewriters, and it pertains, more particularly, to means for shifting a multi-color ribbon adapted for use on front strike machines, *i. e.* that kind known as "visible" writing machines.

The object is to provide a simple and efficient construction by which a multi-color ribbon is normally positioned to expose the writing line on the platen carriage, is controllable by a manual operation to bring one or the other of the two-color sections on the ribbon into writing position, and is automatically moved into the path of the type upon the depression of any one of the key levers so as to secure a printed impression of the selected color.

With the foregoing and other objects in view, the invention embodies a ribbon vibrator slidably fitted on a guide member for the type bars, said vibrator having means for connecting thereto a multi-color ribbon in such way that the ribbon is free to slide through the vibrator and is caused to move with said vibrator when the latter is shifted relative to the guide member, said vibrator and the ribbon therein being normally in a position to expose the writing line. With said vibrator cooperates a system of levers and a device for effecting a variable movement of the vibrator whereby the levers operate in unison with the universal bar and the escapement for automatically moving the ribbon into and out of the path of the type bars upon depressing any one of the key levers, whereas the variable movement device is controllable at will for shifting the ribbon within the vibrator for the purpose of positioning the selected color section of said ribbon in the path of said type bars.

In a practical embodiment of the invention the lever system includes three levers, one of which is connected to the vibrator for directly imparting movement thereto, a second lever is provided with a cam which contacts normally with a cam on the first

lever, and a third lever co-operates with the second lever and with an escapement lever, the arrangement being such that the operation of the escapement to control the platen carriage actuates the lever system to impart movement to the ribbon vibrator. 60

The lever system described is useful, more particularly, in connection with a shiftable guide member of the character disclosed in a prior application Serial No. 656,170, filed October 23, 1911, wherein the guide member and the vibrator are shiftable out of operative positions relative to the platen carriage, the latter being removable from the typewriter in order that the whole machine may be so compactly arranged as to facilitate transportation. Said lever system performs the function, mainly, of permitting the guide member and the vibrator to be turned downwardly and upwardly without disarranging the levers, *i. e.* disconnecting any part of the actuating mechanism for said vibrator to secure said folding movement. 70

The means for effecting the variable movement is a collar positioned on the escapement lever for sliding movement thereon, said collar co-operating with the third lever so as to be movable toward or from the fulcrum thereof and operating, when the escapement lever is actuated, to impart movement to said third lever, the extent or degree of such movement depending upon the distance of the collar from the lever fulcrum. To the collar is connected a rod leading to a shift lever positioned in convenient reach of the operator to change the ribbon at will so as to bring either color section into position for use. 80

In the accompanying drawings, I have illustrated one practical embodiment of the invention, but the construction shown therein is to be understood as illustrative, only, and not as defining the limits of the invention. 85

Figure 1 is a vertical transverse section through a part of a typewriter illustrating the new ribbon vibrator in operative position relative to a platen carriage. Fig. 2 is a vertical section on the line 2-2 of Fig. 1, through certain parts of a typewriter, some of the parts composing the vibrator mechanism being shown in elevation. Fig. 3 is a front elevation, partly in vertical transverse section, and similar to Fig. 1, illus- 100 105 110

trating the vibrator, moved into an out of service position out of the path of the platen carriage or any part thereof. Fig. 4 is a cross section, in the plane of the dotted line 5 4-4 of Fig. 3, illustrating more particularly the out of service relation of the vibrator to the platen carriage. Fig. 5 is a fragmentary plan view illustrating a part of the frame and the shift lever by which 10 the multi-color ribbon may be moved to either of two positions in order to bring its respective color sections into the path of the type bars. Figs. 6 and 7 are vertical sectional views illustrating the two positions 15 of the bar which carries the ribbon vibrator. Fig. 8 is a front elevation with certain parts of the actuating mechanism for the ribbon vibrator in the normal position. Fig. 9 is a plan view of the parts shown in Fig. 8. 20 Fig. 10 is an enlarged view in rear elevation of the ribbon vibrator, the full lines illustrating said vibrator in its normal lowered position, and the dotted lines showing the vibrator in a raised position. Figs. 11 and 25 12 are views in front elevation showing the two operative positions of the ribbon vibrator for the purpose of positioning the ribbon so that the type bars will operate through the respective color sections of said 30 ribbon.

A designates a portion of a typewriter frame, B a pivoted type bar adapted in its normal position to rest upon the cushion b, C a key lever, D a universal lever supported 35 by a cross rod d and provided with a universal bar d', E a horizontal plate or other member forming a support for a platen carriage F, and G a platen mounted in said carriage. The platen carriage is provided 40 with a rack f with which meshes a gear f' on a vertical shaft F' which carries an oscillating escapement wheel F², said parts constituting an escapement mechanism whereby 45 step-by-step movement is imparted to the carriage. Platen G is shown as having suitable hand wheels g for its convenient manipulation, and to this carriage is attached a bar h having paper clips or guides H.

The foregoing parts are usual in a certain kind of front strike typewriter, and no 50 novelty is claimed herein for such parts, for the reason that some or all of the parts constitute the subject matter of other applications for patents heretofore filed by me, 55 more particularly the escapement mechanism. It may be added that said escapement mechanism, in addition to the vibratory and rotatable escapement wheel F² embodies the further element of an escapement lever 60 F³, shown in Figs. 1, 8, 11 and 12 as a bell-crank, the latter being pivoted by a pin or screw f² to a bracket f³. One arm of this escapement lever extends below the escapement wheel so as to lift the same relative 65 to a square portion of the escapement shaft

F', but the other arm of said escapement lever extends downwardly from the pivot f² so that the rod f⁴ may be connected to said arm, the other end of said rod f⁴ being pivoted to an upstanding arm of a bellcrank F⁴, the other arm of said bell-crank lever being in coöperative relation to universal lever D, see Figs. 1 and 3, whereby the operation of the universal bar imparts movement to the escapement. 70

Across the upper front part of the machine and in front of the platen carriage is positioned a horizontal carrying bar I, the same being substantially square in cross section, as shown more particularly in Figs. 6 and 7. This carrying bar is pivotally supported in side members of frame A by suitable screws i, whereby the bar may be rocked or turned on its longitudinal axis, but the bar is held or retained in either of the positions to which it may be adjusted by hand by means illustrated in Figs. 6 and 7. The bar is provided with a plate i' which is attached to one face of the bar by screws i'', the width of the plate exceeding the thickness of the bar. In the path of this plate is a yieldable retaining member I' shown as a spring plate having a curved edge i³, said plate being secured firmly to a member of frame A by a screw i⁴. The retaining plate is normally in frictional contact with plate i' on the rocking bar, such frictional contact between plate i' and the curved edge i³ of the retaining plate being sufficient to hold the supporting bar I in either the operative position shown in Fig. 6, or in the adjusted position illustrated in Fig. 7. 95

The supporting bar carries ribbon guides J, J'; a type bar guide K and a ribbon vibrator L. The ribbon guides are positioned near the respective ends of the supporting bar, each guide consisting of a metal plate which is secured firmly to the bar and said plate having an inclined slot j through which the ribbon is adapted to pass on its way from the ribbon spools (not shown) to the vibrator. 100

The guide K for the heads of the type bar is shown in the form of a plate, one end portion of which is bent part way around supporting bar I, the bent part k of said plate being fastened by screws k' to the rear of supporting bar I, as shown more clearly in Figs. 2, 4 and 10. In the normal position of supporting bar I, the guide plate K extends upwardly from said bar so as to occupy a coöperative relation to platen G. Said plate K is provided at its upper portion with a longitudinal slot K² through which is adapted to pass the head of the type bar B when a key lever C is depressed. In addition to the slot k² in its upper part, the guide plate K is provided with another longitudinal slot k⁴ for a purpose which will presently appear, the upper wall of which 112

acts as a stop in limiting the upward movement of ribbon vibrator L. Said ribbon vibrator L is a plate having the tapering form shown more particularly in Figs. 1, 10, 11, 5 and 12, said plate being positioned close to the rear side of the type bar guide K. The upper part of plate L forming the ribbon vibrator is forked or bifurcated, thereby producing two arms l which are separated 10 by an intervening space, the width of which substantially exceeds the width of type bar guide K. The arms l are cut or slotted to produce tongues l' so that the ribbon will be positioned between the arms and the 15 tongues thereof for the purpose of loosely connecting the ribbon with the vibrator. The ribbon is free to slide through the vibrator under the automatic action of the machine, but the ribbon may be displaced or 20 adjusted by hand into and out of engagement with the tongue-formed bifurcated part of the vibrator. The vibrator is supported or carried by guide K to which said vibrator is slidably connected. As shown, 25 the vibrator is provided with clips m below the forked upper part thereof, which clips are snugly fitted to the respective side edge portions of guide K. The lower part of the 30 vibrator is also connected slidably to guide K by a pin m' which passes through the slot k⁴ of guide K, said pin m' operating to loosely connect said vibrator with one of the series of levers. It will be understood that the pin m' slidably connects the 35 vibrator L to guide K and pivotally attaches a lever O to said vibrator.

It may be stated that pin m' is riveted to plate L and slides freely in vertical slot k⁴ of guide K, one end of the rivet being 40 headed to preclude vibrator L from getting out of position. The vibrator can be detached from guide K by sliding the rivet upwardly until the headed end of said rivet can be drawn through the enlarged upper 45 end of slot k⁴, see Figs. 1 and 11.

Lever O forms one of the series of three levers indicated at O P Q. Lever O is fulcrumed at one end on supporting bar I by a pin or screw o, and this pivoted end of 50 the lever is provided with a cam o', said lever O being normally depressed by a spring O' which is attached to supporting bar I and acts upon the top edge of the lever O to depress the lever and retain vibrator L 55 normally in a lowered position with respect to guide K, whereby the writing line on the paper fitted around the platen G will be exposed to view above the top edge of guide K and between the arms l at the upper 60 forked or bifurcated part of vibrator L, see Figs. 11 and 12.

The second lever P of the series of levers is provided at one end with a short upstanding arm p, the latter being pivoted by a pin 65 or screw p' to a stationary bracket p² fixed

to a stationary part of frame A. Said lever P is provided intermediate its ends with a cam P', the latter extending forwardly from the lever and positioned below the cam o' of vibrator lever O, whereby the movement 70 of lever P will cause cam P' to act upon the cam o' of lever O for the purpose of lifting said lever O and vibrator L. Lever P lies toward the rear of lever O, lever O being on the front side of bar I, whereas 75 lever P is at the rear of bar I, and thus the cam P' of lever P is adapted to extend below bar I in order that said cam P' of lever P will properly contact with cam o' of lever O. Said lever P extends a suitable distance 80 alongside the bar I at the rear thereof, and at its free end lever P is bent downwardly at q and provided with a clip q', whereby lever P is in cooperative relation to lever Q. Said lever Q is in the rear of lever P so as 85 to extend parallel thereto for a suitable distance. At one end lever Q is bent rearwardly at r, and this bent end is pivoted by a pin or screw r' to a plate r² attached to the carriage plate, whereby the lever Q is 90 fulcrumed. Levers P Q are operatively connected by the clip q' of lever P fitting over the free end portion of lever Q, as shown more clearly in Figs. 8 and 9. Levers P Q are pivoted independently of each other, 95 lever P being fulcrumed to the frame and lever Q to the carriage plate, the latter being movable vertically in order to shift the carriage into position to receive impressions from the upper case type on the type 100 bars. The arrangement allows for equal movement of vibrator L in either the raised or normally lowered position of the carriage plate, for the reason that lever Q shifts with the platen whereas lever P is not movable 105 with said platen. Thus, when the platen is raised, lever Q goes up with it and raises end of lever P by clip q', and said lever P acts through cams o' P' to raise vibrator. Lever P and bar I are fast to frame A so 110 as to be always in the same position, but lever Q allows the platen to be shifted without disengaging the ribbon vibrator mechanism. Lever P is operatively related to lever O by the cam P' contacting with the 115 cam o' of the other lever, thus permitting a certain independence of action between the levers when the bar I is rocked or turned on its longitudinal axis, for the purpose, first, of moving the ribbon guides, the type bar 120 guide, and the ribbon vibrator to the out of service position relative to the carriage, shown in Figs. 3 and 4, and second, for retaining the parts in operative relation to each other when the bar I occupies its 125 operative position so that the ribbon guides, type bar guide and the ribbon vibrator will be in such relation to the platen as to properly direct the ribbon into the path of the heads on the type bars when operating the 130

machine. It will be noted that the ribbon guides, vibrator and type bar guide may be folded to an inoperative position or returned to operative position without adjusting any element of the mechanism which imparts movement to the ribbon vibrator, for the reason that the levers O P Q are so related that bar I may be turned in either direction without requiring any hand adjustment of either of said levers.

The vibrator mechanism is actuated by the escapement, and to this end I have provided means whereby the movement of a member of the escapement is communicated to the lever system for actuating the vibrator in unison with the escapement. In the embodiment of this part of the invention shown by the drawings, a collar R is supported on escapement lever F³, said collar being provided with a forwardly extending lug R'. By mounting the collar on the escapement lever, said collar is movable with the escapement lever, and the lug R' of the collar extends forwardly from the collar and below lever Q, said lever resting upon the collar, whereby the upward movement of escapement lever F³ lifts the collar and lever Q, which movement of said lever Q is imparted to lever P by the clip q' of lever O engaging with the free end of lever Q, and as a result of this movement of levers P Q the cam P' acts on cam o' of lever O for the purpose of lifting the vibrator L into an operative position.

It will be noted that the collar R constitutes the means for communicating the motion of escapement lever F³ to the vibrator L. In this connection it is to be noted that said collar R is fitted on the escapement lever for adjustment lengthwise thereof, and this adjustment of the lever takes place with respect to the pivots of levers P Q. Manifestly, an adjustment of the collar toward the free end of lever F³ operates to position collar R close to the pivots of levers P Q and away from the pivot f² of escapement lever F³. Accordingly, when the collar R is at the free end of lever F³ the extent of upward movement of the collar will be greater than were the collar positioned closer toward the pivot f² of lever F³. This collar provides means for imparting variable throw to levers Q P O, and, accordingly, a variable movement is imparted to vibrator L, which variable movement is useful in the present invention for the reason that the vibrator is operated to bring one or the other of the color sections on the ribbon into the path of the heads on the type bars. As a means for shifting collar R to variable positions on the escapement lever, I employ a rod S and a lever S', said rod being connected to the lug R' of the shiftable collar. The other end of rod S is connect-

ed to shift lever S', the latter being fulcrumed at s on a lug s' of the frame, see Fig. 5. Lever S' is at one side of the machine frame and is in a horizontal position so that one end of the lever is within convenient reach of the operator.

When the lever occupies the full line position in Fig. 5, rod S draws collar R toward the pivot f² of escapement lever F³, and when the escapement is operated the levers O P Q are actuated by the movement of the escapement lever so as to raise the vibrator to the position shown in Fig. 14, whereby one color section of the ribbon is brought into the path of the type heads on the type bars. By shifting the lever S' to the dotted line position of Fig. 5, rod S moves the collar R toward the free end of lever F³ and away from its pivot f². Now when the escapement lever is actuated the collar imparts an increased throw to levers O P Q, as a result of which the vibrator will be moved to a higher position on the guide K, as shown in Fig. 12, thus presenting another color section of the ribbon in the path of the type head on the type bars. The vibrator is actuated each time a key is struck, and when pressure is removed from the key, the vibrator is lowered to its normal position, shown in Fig. 10, whereby the writing line is fully exposed to the view of the operator. In this connection it is desired to state that the vibrator is moved to different positions on the guide K depending upon the position of the collar R upon the escapement lever. This position of the collar is determined by the position of lever S'. Assuming that a two color, or black and red, ribbon is used, the mechanism is adjusted to write the letters in black when the lever S' occupies the full line position of Fig. 5, and the collar R occupies the position shown in Figs. 8 and 9, and, accordingly, the vibrator will be moved by the escapement lever operating the system of levers to the position of Fig. 11, thus resulting in the type head striking through the black color section of the ribbon. For writing through the red color section of the ribbon the lever S' is moved to the dotted line position of Fig. 5, and the collar R is shifted toward the free end of escapement lever S³, as shown in Fig. 3. Now when the escapement is actuated by the depression of the key levers, the collar R imparts an increased throw to levers O P Q, and the vibrator is moved to a higher position upon the guide, thus presenting the red color section of the ribbon in the path of the type bars. Obviously, the change from one color to the other of the ribbon may be effected easily and quickly by a simple movement of the shifting lever S'. It has been stated that the guide K and vibrator L are mov-

able into an out of service position for the reason that it is desired to compactly dispose of these parts and position them out of the path of the carriage when the latter is withdrawn from the machine for the purpose of compactly folding the carriage, and the ribbon vibrator, to facilitate storage or transportation of the machine. The actuating mechanism for the vibrator permits the guide K and vibrator L to be easily and quickly turned into the out of service position without dismantling the actuating mechanism or adjusting any of the parts thereof. It will be noted that vibrator L and guide K are carried on supporting bar I for movement therewith to the out of service position shown in Figs. 3 and 4. The lever O partakes of this turning movement of the vibrator and the guide with bar I, for the reason that lever O is connected by pin m' with the guide and the vibrator, but at this point it is noted that lever O is not pivotally or directly attached to levers P or Q. Accordingly, the movement of lever O with bar I, the guide, and the vibrator will take place without disconnecting said lever O from lever P. When the bar and its attached parts are returned to their normal position the cam o' of lever O moves relative to the cam P' of lever P, whereby the movement of the vibrator with the bar and lever O does not disarrange any of the actuating mechanism for the vibrator, nor does it require any manual adjustment or manipulation of any part of the vibrator actuating mechanism.

Having thus fully described the invention, what I claim as new, and desire to secure by Letters Patent is:

1. In a typewriter, the combination with a platen carriage, of a ribbon vibrator supported normally in an operative position relative to said platen carriage for the type bars to coöperate therewith, said ribbon vibrator being shiftable bodily into an out of service position with respect to said platen carriage, in which out of service position the type bars are precluded from coöoperating with said vibrator, and actuating means for said ribbon vibrator comprising a plurality of devices which remain in coöperative relation to each other when the ribbon vibrator is in said normal operative position or is shifted into the out of service position relatively to the carriage.

2. In a typewriter, the combination with a platen carriage, of a ribbon vibrator positioned normally in operative relation to said platen carriage for the type bars to coöperate therewith, said ribbon vibrator being rotatable into an out of service relation to the carriage so that the type bars are precluded from coöoperating therewith, and actuating means for said ribbon vibrator, said actuat-

ing means being in operative relation to said ribbon vibrator in both the normal position and in the out of service position thereof.

3. In a typewriter, the combination with a platen carriage, of a ribbon vibrator positioned in operative relation to said platen carriage for the type bars to coöperate therewith, said ribbon vibrator being shiftable into an out of service position with respect to the platen carriage to thereby preclude the type bars from coöoperating therewith, actuating means for said ribbon vibrator, said actuating means being in operative relation to the ribbon vibrator in the operative and the out of service positions thereof, and means effective through said actuating means for varying the effective throw of said ribbon vibrator.

4. In a typewriter, the combination with a platen carriage and an escapement mechanism, of a ribbon vibrator occupying an operative position relative to said platen carriage for the type bars to coöperate therewith, said ribbon vibrator being shiftable into an out of service position with respect to said carriage for precluding the coöperation of the type bars therewith, and means actuated by the escapement mechanism for imparting movement to said ribbon vibrator, said vibrator-actuating means being in operative relation to the vibrator and the escapement mechanisms in both the operative and out of service positions of the vibrator.

5. In a typewriter, the combination with a platen carriage and an escapement mechanism, of a ribbon vibrator occupying an operative position relative to said platen carriage for the type bars to coöperate therewith, said ribbon vibrator being shiftable into an out of service position with respect to said carriage for precluding the coöperation of the type bars therewith, means actuated by the escapement mechanism for imparting movement to said ribbon vibrator, said vibrator-actuating means being in operative relation to the vibrator and the escapement mechanisms in both the operative and out of service positions of the vibrator, and means effective through the vibrator-actuating means for imparting variable movement to said vibrator.

6. In a typewriter, the combination with an escapement mechanism, of a ribbon vibrator normally occupying an operative position and rotatable at will into an out of service position, and a system of levers one of which is operable by the escapement mechanism and another of which coöperates with said vibrator for imparting movement thereto, the levers of said system being in operative relation to each other and to the vibrator in the operative and in the out of service positions of said vibrator.

7. In a typewriter, the combination with an escapement mechanism, of a ribbon vibrator for carrying a multi-color ribbon, said ribbon vibrator being rotatable into an out of 5 service position, a system of levers actuated by the escapement mechanism for operating the ribbon vibrator when in normal position, and means controllable at will for varying the throw or movement of said vibrator 10 to position either color section of a multi-color ribbon into position for use.
8. In a typewriter, the combination with an escapement mechanism, of a ribbon vibrator for carrying a multi-color ribbon, 15 said ribbon vibrator being rotatable into an out of service position, a system of levers actuated by the escapement mechanism for operating the ribbon vibrator, and permitting the latter to be moved into the out of 20 service position, and means controllable at will for varying the throw or movement of said vibrator to position either color section of a multi-color ribbon into position for use.
- 25 9. In a typewriter, the combination of a ribbon vibrator, a lever connected thereto, a second lever coöperating with the first lever, means whereby the vibrator and the first lever may be shifted relative to the second 30 lever to position said vibrator into an operative or an out of service relation to a platen carriage, and means for operating the second lever.
10. In a typewriter, the combination of a ribbon vibrator movable into operative and 35 out of service relations to a platen carriage, a lever connected to said vibrator and movable therewith, a second lever coöperating with the first lever to permit the aforesaid 40 lever to be moved with the vibrator, and escapement actuated means for operating the second lever.
11. In a typewriter, the combination of a ribbon vibrator movable into operative and 45 out of service relations to a platen carriage, a lever connected to said vibrator and movable therewith, a second lever having means for normally retaining the two said levers in operative relation, and means for actuating 50 the second lever.
12. In a typewriter, the combination of a ribbon vibrator movable into operative and out of service relations to a platen carriage, a member for actuating said vibrator 55 and movable therewith into such out of service and operative positions, a second member normally in operative relation to the first member, and means for automatically operating the second and first members.
- 60 13. In a typewriter, the combination of a ribbon vibrator movable into operative and out of service relations to a platen carriage, a member for actuating said vibrator and movable therewith into such out of service 65 and operative positions, a second member normally in operative relation to the first member, means for operating the second member
- normally in operative relation to the first member, means for operating the first member through movement imparted to the second member, and means controllable at will for varying the effective throw or movement 7 of said members.
14. In a typewriter, the combination with an escapement, of a ribbon vibrator movable into an out of service position, a lever connected therewith, a second lever coöperating with the first lever, a third lever in operative relation to the escapement and the second lever, and means for effecting a variation in the throw of the third lever.
15. In a typewriter, the combination with an escapement, of a ribbon vibrator movable into an out of service position, a lever connected therewith, a second lever coöperating with the first lever, a third lever in operative relation to the escapement and the second lever, a member shiftable to variable positions relative to the third lever, and means for imparting movement to said member.
16. In a typewriter, the combination with an escapement, of a ribbon vibrator movable into an out of service position, a lever coöperating with the ribbon vibrator in the operative position thereof, a second lever having a member for imparting movement to the first lever, and a third lever actuated by the escapement and operating the second lever.
17. In a typewriter, the combination with an escapement lever, of a ribbon vibrator movable at will into an out of service position, a lever coöperating with said ribbon vibrator in the operative position thereof, a second lever operated by the movement of the first lever, a third lever in operative relation to the escapement and the second lever, and a device actuated by and shiftable relative to the escapement lever, said device operating to impart variable movement to the third lever.
18. In a typewriter, the combination with an escapement lever, of a ribbon vibrator, a lever connected therewith, a second lever coöperating with the first lever, a third lever in operative relation to the escapement and the second lever, a collar carried by the escapement lever and coöperating with the third lever, and means for shifting said collar to variable operative positions relative to the third lever and the escapement lever.
19. In a typewriter, the combination of a ribbon vibrator movable to out of service and operative positions, a lever connected to and movable with said vibrator, a second lever supported independently of the first lever, said second lever having a member which is normally in operative relation to the first lever, and escapement actuated means for operating the second lever.
20. In a typewriter, a rockable supporting bar, a ribbon vibrator carried by said 1

bar and movable therewith into out of service and operative positions, and means for retaining said bar in different positions to which it may be shifted.

5 21. In a typewriter, a rockable supporting bar, a ribbon vibrator carried by said bar and movable therewith into out of service and operative positions, a ribbon guide attached to said bar, and means for retaining 30 said bar in different positions to which it may be shifted.

5 22. In a typewriter, a rockable supporting bar, a ribbon vibrator carried by said bar and movable therewith into out of service and operative positions, a plurality of 35 ribbon guides carried by the bar and positioned at the respective sides of the vibrator, and means for retaining said bar in different positions to which it may be 40 shifted.

5 23. In a typewriter, the combination with a carriage platen, of a movable type-bar guide, a ribbon vibrator slidably connected thereto, and actuating mechanism for said 5 ribbon vibrator.

24. In a typewriter, the combination with a carriage platen, of a rockable supporting bar, a type-bar guide attached thereto, a ribbon vibrator slidable relative to the type-bar guide, and actuating mechanism for said 30 ribbon vibrator.

25. In a typewriter, the combination with a frame, a platen, and an escapement, of a ribbon vibrator rotatable into an out-of-service position, actuating mechanism for 35 said ribbon vibrator embodying a plurality of members, one of which is operable in unison with a shifting movement of the platen, and another is actuated by the escapement, and means for varying the throw 40 of said actuating mechanism so as to impart variable movement to said ribbon vibrator.

In testimony whereof I have signed my name to this specification in the presence of two subscribing witnesses.

GEORGE F. ROSE.
